MAXIMILIAN MÜLLER, OF TEMPELHOF, NEAR BERLIN, GERMANY.

BAND BRAKE ACTING IN BOTH DIRECTIONS OF ROTATION.

Application filed April 4, 1922. Serial No. 549,585.

To all whom it may concern:

Be it known that I, MAXIMILIAN MÜLLER, a subject of Czechoslovakia, residing at Tempelhof, near Berlin, Germany, have invented certain new and useful Improvements in Band Brakes Acting in Both Directions of Rotation, of which the following is a specification.

The present invention relates to a band-brake, which will act in both directions of rotation and it is characterized in that the pulling force at the engaging end of the strap or band is created by means of the friction on the brake drum.

In order to carry this idea into practice various ways are diagrammatically illustrated in the drawings, in which the same reference characters designate like parts throughout;

Figs. 1, 2, 3 and 4 are side views of various forms of the invention of which Fig. 4 shows the preferred form,

Fig. 5 is a fragmentary side view of another form of the invention,

Figs. 5^a, 6, 7 and 8 are side views of still other forms of the invention,

Fig. 9 is a side view of a solenoid, and

Fig. 10 shows a wiring diagram for an electromagnetic brake.

In the first place the band proper may be utilized as a friction-source for the pulling force in said band. For instance in Fig. 1 the shaft to be braked is designated by "A" and on said shaft is keyed a braking drum 1. Around this drum the strap 2 2' is led, the ends of which lead to the fixed point 4. If a roller 43 is pressed upon said band, the latter is conducted by the rotation of the drum between the drum and said roller in the direction of rotation and under the pressure of the roller 43 a friction is caused between the band and drum, which creates a pulling force in the said band, so that a braking action is exerted. If the drum is rotating in the direction of the arrow as indicated in the drawing, the end 2 of the band is tightened and exerts a braking action, while the end 2' of the band becomes slack.

Another mode of execution is illustrated in Fig. 2, in which the embraced sector becomes essentially larger. A again represents the shaft, 1 the drum of the brake, 2 and 2' the band. The latter is provided

with stops riveted upon it, consisting for instance of flat iron members 5 and 5', comprising stops, which are capable of abutting against fixed stops 6 or 6'. It is supposed that the band is entirely flexible or at least is provided with a flexible part between the points 5 and 5'. If the roller 43 is pressed down again, the aforesaid procedure will be repeated, and if the direction of rotation of the drum 1 is counter clockwise as shown by the arrow, the stop 5 on the band will abut against the fixed stop 6 and a powerful braking action will be obtained while the portion of the band between the roller 43 and the stop 5 on the band becomes slack and is forced up. This stage is illustrated in Fig. 2.

If the band proper is utilized as a source of friction, the characteristic feature of the invention is, that one roller is pressed against the band in such a way that an arc of the drum engages with the corresponding arc of the band according to the direction of rotation either to the left hand or to the right hand of the point where the roller is applied.

Instead of employing the band proper as a source of friction, preferably a special friction member for instance as illustrated in Fig. 3, an electromagnet can be used. Here again are provided the brake drum 1, the band 2 and 2' with its stops 5 and 5'; 6 and 6' are fixed stops as illustrated in Fig. 2. The magnet 20 upon which an exciting coil 8 is wound, is connected with both ends of the band by means of the chains 21 and 22. If the magnet is excited it will adhere to the brake drum, and be taken along by the latter and will thus create a pulling force on the chains according to the direction of rotation, so that the band will engage and cause a braking action.

The preferred form of the invention is illustrated in Fig. 4 in which all parts are similarly designated as in Fig. 3 but in lieu of a magnet a roller 3 is provided. If the latter is pressed by any suitable mechanical means against the drum 1 it will be turned by the friction and according to the direction of rotation either the chain 21 or 22 will be tightened thus producing a braking action.

This mode of execution is superior to all those already described since it is very easy

to obtain a gearing between the frictional power upon the roller and the pulling force on the band. It is only necessary to construct, for instance, the roller as a stepped 5 roller in such a manner, that the frictional force of the brake drum acts upon the larger radius of the roller, while the chain leading to the end of the band engages a smaller radius of the said stepped roller.

10 Another mode of execution is illustrated in Fig. 5, in which the difference consists merely in that the roller does not press the drum directly, but that a special friction member 9 is arranged between roller 43 and drum 1 from which member the chains 21 and 22 lead to the ends of the band. It is obvious that as soon as a mechanical pressure is exerted upon said roller, the friction member 9 is carried along by the braking 15 drum while the latter is rotating, so that a pulling force is created and either the chain 21 or 22 is tightened according to the direction of rotation, causing the braking action.

A similar arrangement is shown in Fig. 25 5a. Here the roller is substituted by a toothed wheel 3', which is in engagement with the friction member 23 and the chains engage the toothed wheel. The advantage gained is so to speak considerably greater 30 than the ratio of the two radii. The reason for this is that the force which is created in the chain can be resolved into two components, the direction of one of which is identical with the direction of the roller-lever, 35 whereas the direction of the second component is that of the radius of the brake drum. This latter component has to be added to the external pressure by which the roller is pressed against the drum.

40 A small mathematical deduction shows that if Z is the force of the chain, P the exterior pressure with which the roller is pressed against the drum, r' the small radius of the roller, r'' the large radius of the 45 roller, R the radius of the brake drum and u the coefficient of friction between the roller and drum; then follows:—

$$Z = \frac{u \times P}{\frac{r'}{r''} - u \sin \alpha}$$

whereas

$$\cos \alpha = \frac{Rr'}{Rr''}$$

55 whereas on first glance it would appear that Z is equal to

$$\frac{uP}{r'/r''}$$

60 These new brakes may particularly be employed with vehicles, since they consume only an extraordinarily small amount of power. For actuating, such brakes require hardly one hundredth part of the work required

by the block-brakes used almost exclusively up to the present. This advantage is derived from the fact that with these new brakes the force of the vehicle or car will, while braking, accomplish a great portion 70 of that work, which had to be done by hand in the block-brakes hitherto used.

But if these band brakes are employed in cars trouble will arise under certain circumstances, on account of the braking drum 75 being secured to the axle of the car, while the band proper is attached to the frame of the car. As the axles are allowed a certain free play in relation to the car, tensions will occur in the band during the braking operation, which cause a violent and undesirable shaking. This will at once disappear, if the whole braking device is arranged upon the axle of the car, as illustrated in Fig. 6, in which A designates the axle of 80 the car, upon which is tightly keyed the brake drum 1. Now on the shaft of the braking drum a sliding bearing is provided, which rests in a cast steel frame 12, which carries the solenoid 24, and the roller-lever 7 85 with its pivot point 25, in which the roller 3 is pivoted. The fixed stops 6, 6' are rigidly secured to the frame 12 being either screwed or riveted to it or cast thereon. Finally the frame 12 is suspended by means of any 90 suitable intermediate member 11' on the frame 13 of the car. 14 represents the wheel of the vehicle pertaining to said axle A and 15 the rail. Instead of placing the bearing of the frame upon the shaft of the 95 braking-drum it may of course just as well bear directly on said axle. It is also possible to make use of the axle boxes of the car for that purpose, or of the axle bearings 100 of electric motors if such are provided. The 105 important point always remains, that a special frame is bearing on the axle either directly or indirectly in such a manner that it only executes a rotating movement in relation to said axle.

110 Operating these new band brakes can be effected in a known manner either by hand, mechanically or by air or electrically by magnets. Various important improvements are possible with electrical operation such 115 as the following:

On the one hand the pressing force can be effected by means of a magnet, as shown in Fig. 3. But the operation can also be effected electrically by interposition of the 120 roller as shown in Fig. 7. A solenoid is provided here which will pull its piston if it is excited by a current and thus turn the roller lever 7' pivoted at point 25' in such a way, that the roller 3 causes a pressure. The remaining parts of this illustration correspond 125 with the construction shown in Fig. 4 and will be understood without any further explanation. 26 is a spring designed to withdraw the roller after the braking operation

and to pull out the plunger of the solenoid again.

In this arrangement an electric current is active during the braking operation and the control of the braking power can be simply effected in that the intensity of the magnet or solenoid is increased or decreased.

It is however possible to effect quite a new electrical operation, in which during the braking action no current is active. If the pressing force of the roller is effected by means of the expansion of springs, which after the braking action is finished, are again put under tension by means of an electromagnet, it is hereby accomplished, that during the braking operation disturbances in the conductor, as for instance, defective controller or coupling contacts between the cars or breakage in car-wiring are without the least influence on safety of the brake. Of course part of the train which has become detached for some cause, will be braked automatically. For compressing the spring preferably solenoids are employed as electromagnets.

The electric energy required for compressing the spring by means of the solenoid can be supplied by a current from over-head conductors, since with these brakes the absence of current in the over-head conductor will not prevent the braking action, but on the contrary it will permit such action. Constructional forms of this kind of actuation are illustrated in Figs. 8 and 6. 7" is the roller lever pivoted at 25" and 24 the solenoid. The lever 7" is pivoted to the stationary member 12' which has a stop 6 at one end thereof which cooperates with the stop 5 on the brake band. The core of the latter extends far beyond it and carries at this free end a spring-plate and between this spring-plate and the casing of the solenoid is disposed the braking spring 10. If the solenoid is energized the latter will generate such a power, that the spring 10 is compressed by the aid of the spring-plate. In this state, represented in Figs. 6 and 8 the spring is compressed, the roller is not in engagement with the drum and no braking action is effected. This position of the brake is maintained when driving but if the current in the solenoid is interrupted the spring advances the plunger of the solenoid, and the spring-plate abuts against the roller lever 7" turning the latter to such an extent that the roller 3 is pressed against the drum 1 with considerable force. Thus a braking action takes place. Braking could of course also be effected by hand without releasing the tension of the spring, if the roller lever 7" of Fig. 8, is turned by a force applied at 11.

65 The springs must of course be kept com-

pressed while ready for action and for that purpose a locking-device would be required, if the current is to be conserved. The best method for locking is to construct the solenoid compressing spring, in such a way, that it will always retain as much power, even if the current is very weak, which will be sufficient to maintain the spring compressed. Fig. 9 illustrates this method. All magnets having a movable core will require for said core a non-magnetic guiding in order to warrant a frictionless working, but such non-magnetic guiding decreases considerably the carrying power in the end position. If provision is made for a magnetic bridge at this place, the pulling power in the end position can be increased almost twofold, that is to say a certain pulling force, corresponding with that of the compressed spring, can be obtained by a far less consumption of current. In Fig. 9, 27 designates the core of the solenoid, 28 the coil, 29 the casing, and 30 the non-magnetic guiding of brass, bronze or the like. If the cylindrical core is equipped with a fixed neck or ring 31 in such a manner that this ring neatly abuts against the casing in the end position of the magnet core, it will bridge the non-magnetic guiding in the end position and obviously the carrying power is almost twice as great. For the member 31 the expression adhering ring could be applied.

Thus it is possible to maintain the tension of the spring by a weak current, as the closed circuit current, is flowing through the solenoid.

The intensity of the braking power depends on the strength of the spring and to what extent it is released. If the release is small, the less the core of the solenoid can advance. Thus a means is provided for adjusting the force of the brake previous to a braking action, as the distance which the plunger of the solenoid is permitted to advance, is limited. This is effected in a simple manner by adjustably constructing the solenoid, as illustrated more plainly in Fig. 6. In the latter a slide (16) is cast to the solenoid, a screw spindle (17) turning in said slide, and adapted to be manipulated from the driver's place by means of bevel wheels and rope pulley. The driver is thus enabled to decrease or increase the braking power even during the operation of the train according to the condition of the track and the load. He will require less braking power, when the wheels of the car slide on slippery rails and with an empty car, than with an overcrowded car on dry rails.

But such regulation would turn out to be too circumstantial, if it would take place during the braking operation, and besides, the trailer cars could not be controlled from

the driver's platform. But a much easier means for controlling the braking power during the braking operation is available here in so far, as the pulling force of the solenoid will act contrary to the force of the spring. If during the braking operation a certain current is led through the solenoid, and which current must of course be less than that required for the compression of the spring, the said solenoid will act with a certain force against the pressure of the spring, that is to say it will reduce the latter and in consequence the braking power.

15 In Fig. 10 a switching diagram is shown, which will explain this operation. (R) is a common regulating switch, whose regulating lever turns about the point 32. (S) O a b c d e are the different positions of said regulating lever, 33 and 34 are resistances, and between the switching steps a and e are likewise provided some resistances. 35 is the coil of the solenoid, 36 is a ground connection and 37 the point from which current is supplied, for instance the over-head conductor. If the driver moves the handle of the regulating switch to the position (S) a sufficiently strong current will flow through the solenoid for the latter to compress the spring. If he moves the handle of the regulating switch to the position (O) the resistances 33 and 34 are connected in series with the coil of the solenoid and the sum of these resistances is selected in such a manner, that the closed circuit current will appear, that is to say a certain small strength of current, which will just suffice to keep the springs compressed. If the driver wants to apply the brakes, he moves the handle from O to a; while the current is thus interrupted for an instant, the coil 35 of the solenoid is free of current, the plunger of the solenoid advances and a powerful braking action would follow. But as soon as he reaches the contact a current again flows into the solenoid, whose pulling power as explained above will decrease the pressure of the spring. Thus a weak braking action is effected to the same extent as the driver by advancing to the positions b, c and so on is connecting up the resistances, the intensity of the current in the solenoid decreases and in consequence its pulling power; so that the pressure of the springs is more and more increased and accordingly the braking power.

I claim:

1. In a brake mechanism comprising a brake drum; a band associated with said drum; band stops on said band; stationary stops adapted for association with said band stops; and a roller intermediate said stationary stops and connected to said band.
2. In a brake mechanism comprising a

brake drum; a band associated with said drum; band stops on said band; stationary stops adapted for association with said band stops; a roller mounted for frictional contact with said brake drum; and means whereby said brake band will tighten itself around said brake drum when said roller contacts with the brake drum.

3. In a brake mechanism comprising a drum and a brake band associated therewith; said band having stops thereon; stationary stops associated with said band stops; a roller adapted to be forced against said drum; and means whereby said band will tighten itself around the drum when the roller is forced against said drum.

4. In a brake mechanism comprising a drum and a brake band associated therewith; said band having stops at each end thereof; stationary stops for association with said band stops; a roller adapted to be forced against said drum; and a connecting member secured to each end of the band and at the other end to a common point on said roller; said point lying upon a smaller diameter than that of the external diameter of the roller.

5. In a brake mechanism comprising a drum and a brake band associated therewith; said band having stops at each end thereof; stationary stops for association with said band stops; a roller adapted to contact with said drum; and means whereby an arc of the band will engage an arc of the drum when the roller is forced against said brake drum.

6. In a brake mechanism comprising a drum and a brake band associated therewith; means associated with the ends of said band for preventing rotation of one end of said band dependent on the direction of rotation of said drum; a roller adapted to be forced against said drum; and a connecting member secured to each end of the band and at the other end to a common point on said roller, said point lying upon a smaller diameter than that of the external diameter of the roller.

7. In a brake mechanism comprising a brake drum; a band associated with said drum and having two ends; a roller connected to and intermediate of the ends of said band; and means for preventing rotation of said band when the roller is forced against said drum.

8. In a brake mechanism comprising a brake drum; a band associated with said drum and having two ends; means associated with the ends of said band for preventing rotation of the band; a roller adapted to contact with the drum; and means connected at one end to an end of said band and at the other end to a point on the roller.

9. In a brake mechanism comprising a
brake drum; a band associated with said
drum and having two ends; means asso-
ciated with the ends of said band for pre-
venting rotation of the band; a roller adapt-
ed to contact with the drum; and means
connected at one end to an end of said band
and at the other end to a point on the roller,
said point lying upon a smaller diameter
than the diameter of the roller. 10

In testimony whereof I have affixed my
signature.
